UNITED STATES PATENT OFFICE

132,508

DESIGN FOR A LACE

Isaac Zendman, Jr., New York, N. Y.

Application April 25, 1942, Serial No. 106,706

Term of patent 3½ years

To all whom it may concern:

Be it known that I, Isaac Zendman, Jr., a citizen of the United States of America, residing in New York city, county of New York, and State of New York, have invented a new, original, and ornamental Design for a Lace, of which the following is a specification, reference being had to the accompanying drawing, forming part thereof, wherein the figure is a plan view of a piece of lace showing my new design on a dark background so as to bring out more clearly the details thereof.

I claim:

The ornamental design for a lace, substantially as shown and described.

ISAAC ZENDMAN, JR.
